CLAIM

The ornamental design for an eyebrow shear, as shown and described.

DESCRIPTION

FIG. 1 is a perspective view of the eyebrow shear showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof;

FIG. 9 is an enlarged view, of circled portion 9, of FIG. 8, thereof; and,

(Continued)

FIG. 10 is an enlarged view, of circled portion 10, of FIG. 3, thereof.

The broken lines throughout the drawing figures depict portions of the eyebrow shear that form no part of the claimed design.

The dot-dash broken lines depict the boundaries of the FIGS. 3, 8, 9 and 10 enlargement that forms no part of the claimed design.

1 Claim, 10 Drawing Sheets
